UNITED STATES PATENT OFFICE.

ARTHUR H. BLACKBURN, OF MATTEAWAN, NEW YORK.

SOOT-SCRAPER.

No. 828,996.

Specification of Letters Patent.

Patented Aug. 21, 1906.

Application filed March 25, 1905. Serial No. 251,954.

To all whom it may concern:

Be it known that I, ARTHUR H. BLACKBURN, a subject of the King of England, residing at Matteawan, in the county of Dutchess and State of New York, have invented 5 certain new and useful Improvements in Soot-Scrapers, of which the following is a specification, reference being had to the drawings accompanying and forming part of the 10 same.

My invention relates to reciprocating soot-scrapers of the general type shown in the patent to Edward Green, No. 513,917, for dislodging soot from the pipes of fuel-economizers, air-heaters, and other apparatus in which 15 pipes are exposed to gases of combustion.

The object of my invention is to improve such scrapers, so that they will produce a clean scrape and not leave portions of the pipe 20 covered with soot, and also to prevent the soot dislodged from the pipe from accumulating between the pipe and the scraper, thereby lessening the effectiveness of the latter.

To these ends the invention consists in the 25 novel features, arrangements of parts, and combinations of elements hereinafter described, and more fully set forth in the claims.

Referring now to the drawings, which show 30 convenient embodiments of the invention, Figure 1 is a perspective view of one section of a scraper; and Fig. 2 is a perspective view of a section, showing a slightly different construction.

Each scraper-section consists, essentially, 35 of upper and lower cutters 1 2, each being a segment of a ring joined by a connecting-bar 3. Each cutter is concave on its inner side to provide upper and lower cutting edges 4 5. The lower edge 5 is continued upward on the 40 connecting-bar 3 by a triangular or pointed extension 6. The effect of this construction is to throw the soot to either side instead of

allowing it to accumulate on the edge 5 in the space between the bar 3 and the pipe upon which the scraper operates, as sometimes 45 happens with scrapers in which the cutting edge lies wholly in one plane—that is, runs straight across the connecting-bar. It can also be sharpened readily, as the edges of the pointed extension can easily be reached by a 50 grinding-tool, as a file or emery-wheel.

Fig. 2 shows the upper or lower half of a modified construction. In this case the pointed extension 7 extends farther up the connecting-bar 8, and to save weight and 55 metal the center of the same is made open, as shown at 9.

Both forms are simple and cheap to manufacture, being easily made by casting in the usual way. 60

What I claim is—

1. In a soot-scraper, the combination of a connecting-bar, a ring-segment at the end thereof arranged transversely thereto and having a scraping edge provided with an extension of substantially triangular form extending backward upon the connecting-bar, providing a continuous edge from the ends of the ring-segment to the point of the said extension, as set forth. 65 70

2. In a soot-scraper, the combination of a pair of ring-segments having scraping edges, and a connecting-bar therefor, one of said ring-segments having a substantially triangular extension of its cutting edge, extending 75 upon, and toward the center of, the connecting-bar, providing a continuous edge from the ends of the said ring-segment to the point of the extension, as set forth.

ARTHUR H. BLACKBURN.
